G. BROWNING

SAFETY RAZOR

Filed May 22, 1922

Patented May 6, 1924.

1,493,065

UNITED STATES PATENT OFFICE.

GEORGE BROWNING, OF CHICAGO, ILLINOIS, ASSIGNOR TO LEANDER H. LA CHANCE, OF CHICAGO, ILLINOIS.

SAFETY RAZOR.

Application filed May 22, 1922. Serial No. 562,592.

To all whom it may concern:

Be it known that I, GEORGE BROWNING, a subject of the King of Great Britain, residing in the city of Chicago, in the county of 5 Cook and the State of Illinois, have invented certain new and useful Improvements in Safety Razors, of which the following is a specification, reference being had to the accompanying drawings, forming a part 10 thereof.

This invention relates to safety razors of the reciprocating-blade type, and has for its general object to simplify and otherwise improve the construction of a razor of the kind 15 mentioned. This object I attain chiefly by employing fewer parts in the design, and by designing each part thereof with economy of manufacture in view.

One of the special advantages attaching to 20 the structure here shown is that it provides a means of the utmost simplicity for translating a straight-line reciprocating motion of one member into a straight line reciprocating motion of the blade along a line at 25 right angles to that of the first-mentioned motion. Another special feature is a novel mounting and fastening for the main guard, whereby said guard is latchable in either open or closed position by devices of 30 simplicity which eliminate the manually operated clamping or latching parts previously employed. The invention, therefore, consists in the features and elements of construction and their combinations, hereinafter 35 described and shown in the drawings, as indicated by the claims.

In the drawings:

Figure 1 is a side or end elevation of a 40 safety razor embodying the invention, omitting a portion of the handle.

Figure 2 is an enlarged plan view taken in section as to the guard only, upon line 2—2 on Figure 1, portions of the blade and comb guard being broken away.

Figure 3 is a detail section taken as indicated at line 3—3 on Figure 2, the handle being broken away.

Figure 4 is a detail view of portions of the pivoted guard and frame.

Figure 5 is a detail section showing the snap mounting of the guard.

Figures 6 and 7 are perspectives of two of the frame parts, detached.

Figure 8 is a fragmentary plan view of a modified form of blade.

Figure 9 is a detail section taken as indicated at the line 9—9 on Figure 3.

As shown in the drawings, the frame of the razor is constructed of sheet metal and comprises a handle-supported part, 1, 1^a, hereinafter termed a yoke; a bottom plate, 2, provided with lugs, 3, for supporting the ends of the comb guard, 4; and a top plate, 5.

The yoke, 1—1^a, forms a spacer between the said top and bottom plates, which are fastened in position upon the part, 1, with two rivets passed through hooks or bends, 6, in the ends of the lateral parts, 1^a, of the yoke, as very clearly indicated by dotted lines on Figure 2. The lower heads of these rivets are indicated at 7, the upper heads, at 8. These upper heads are given a cylindric form whereby they serve as guide-studs for the reciprocative razor blades, 9.

The central lug, 10, of yoke, 1—1^a, has a threaded hole for the reception of a reduced threaded extension on the handle, 12, which is of the ordinary or any preferred kind. The bottom plate, 2, shown detached by Figure 6, has the two holes, 13, for the rivets, 7, the oppositely extended lugs, 3, having rivet-holes, 14, and a pair of bearing brackets, 15, struck down as shown and provided with axially aligned circular holes, 16. This plate, 2, is notched out at 17 to a depth equal to the thickness of metal of yoke, 1—1^a, to receive the portion, 10^a, (Figure 3), where the lug, 10, first branches from the body of the yoke. This makes the back of the yoke flush with the rear edge of the plate, 2, (see 90 Fig. 1).

The normally immovable guard, 4, is of a known type and hence requires no description. It is U-shaped in cross section and has enlarged end portions, 19, which straddle the ears, 14, on part, 2, and are secured thereon by rivets, 20, which may be ordinary rivets or of a special type shown and described in a certain pending application by me, bearing Serial Number 491,683, filed August 12, 1921, for improvements in safety razors. The razor blade, 9, is preferably of the standard wafer type except as hereinafter noted. The blade shown in the drawing has two shaving edges, 22, being reversible. Its 100 guide-slots, 23, engage the heads or guide- 105

studs, 8, and the rearward portion of the blade rests upon antifriction bosses, 24, on plate 5.

The blade as shown in Figure 2 has an oblique slot, 31, therein, located with the center of the slot at the center of the blade in both directions, and the central position lengthwise is due only to the construction and arrangement of the driving mechanism. 10 The blade is actuated by a pin, 25, carried rigidly by the end of a pitman, 26, which is driven in the present case by a one-piece crank shaft, 27, whose two journals, 28, are operatively engaged with a pair of traction 15 rollers, 29. The driving pin, 25, projects through a guiding slot, 30, in plate 5, a sufficient distance to engage the blade-slot, 31, and is permanently fixed to the pitman 26 by means of a stud, 32, driven through the 20 pitman into the pin, 25, the end of stud, 32, resting slidably on frame-plate, 2. Friction is minimized by convexing the end of the stud, as shown in Figure 3.

As shown in Figure 3, the pitman-head, 25 34, is economically formed by bending the end of the pitman into an eye, 34.

The traction rollers, 29, are provided with peripheral teeth, 35, which preferably are given a rake in the proper direction for 30 obtaining a high coefficient of traction between these rollers and the surface to be shaved. The bores for the shaft, 27, are desirably of a size to pass freely thereover, and the driving engagement is effected by 35 cutting diametric or radial slots, 36, in the inner hubs, 37; these slots fit over the respective bends of the shaft without being forced. These crank shaft bends hold the rollers outwardly in spaced relation to the 40 bearing brackets, 15, as shown.

It is apparent that rotation of said rollers will impart a straight-line reciprocation to the pitman in relation to, e. g., section line, 3—3; but it is also evident that the term, 45 "straight-line", does not imply that the entire pitman travels in a straight line in the plane of section, 3—3 owing to the oscillation of its driven end. In the appended claims, the term, "straight-line", is to be 50 construed as in the first sense above mentioned. The direct operative engagement between the blade and the actuating pitman which is effected by the protrusion of the pin, 25, into the slot 31, avoids the use of 55 any interposed operating part and thus renders the construction extremely simple. It will be understood that the arms, 15, have resilience enough to be sprung apart and passed over the ends of journals, 28, and 60 will then spring into place.

The said reciprocation of the pitman with its driving pin, 25, will impart the required rapid reciprocative movement to the blade, and the pin will clear the ends of the slot, 65 31, at the ends of its strokes. As this slot,

31, is straight from end to end, the blade will make but one stroke for each stroke of the pitman; but, if a blade provided with an irregularly-shaped slot of constant width is employed, the number of strokes performed by the blade will be multiplied. I have found that the slot, 38, shown in a blade, 39, (Figure 8), has the characteristics most desired, which are, to double the frequency of the blade strokes, and to 70 increase the velocity of travel of the blade. The angular form of this slot has the effect of compelling the blade to start and stop suddenly, which is a desirable point in a razor of this type. It will be obvious that 75 this modified form of slot does not affect the reversibility of its blade.

The driving pin, 25, might of course be provided with an antifriction roller. However, said pin may be made of harder metal 80 than the blades, and the latter will be replaced from time to time. The latter will also lubricate the walls of the slot and reduce the friction between it and the pin, 25.

It only remains to describe my present 90 improvements in hinging and fastening the guard-plate, 40, to the frame of the razor. As shown in Figure 2, the frame-plate, 5, is provided close to its rear edge, with a pair of narrow slots, 41. The metal, 42, between each slot, 41, and the edge of the plate is non-circular in sectional form, being preferably as shown in Figure 5, square in section. These two portions, 42, which might be called pivots, are offset from the plane 95 of the plate by bending the metal along its length (see 5^a, Figure 2) not shown. The guard plate, 40, is provided with a pair of integral hinge members, 43, bent around the respective pivots as shown, in such a 100 manner that the guard will be held yieldably at the open position indicated on Figure 5, when turned to that position. When the guard is turned about its pivots, 42, the members, 43, of course yield and then reclose upon them by resilience. The slots, 41, are about twice as long as the hinge members, 43, to allow of lengthwise shifting of the guard for operating my novel integral guard-lock, which comprises a small angular lug, 44, on the guard between hinge members, 43, and a small coacting angular lug, 45, on the plate, 5. These lugs are so positioned that when the guard is closed and caused to register endwise with said plate, the lug, 44, will overlap the lug, 45, as shown in Figure 1, thus forming positive means for holding the guard in closed position. The two lugs coengage frictionally 115 also, which prevents accidental release of the movable lug. This friction might be increased by imparting a slight twist to the lugs as indicated by Figure 9, whereby a wedging effect would be obtained.

It is now apparent that the hinge and 130

latch structure described is very simple, and is easily manipulated by manipulating the guard alone, without the use of any separate clamp or latch-piece. Preferably, I cut a recess, 46, in the plate at one side of lug, 45, to receive lug, 44, of the guard when the guard is in open position.

I claim:—

1. In a safety razor, a blade guided for reciprocation parallel to its cutting edge, a blade-actuating member mounted for reciprocating motion in a direction transverse to the blade's reciprocation and having direct operative engagement with the blade; and means to automatically drive the blade-actuating member.
2. In the combination defined in claim 1, the direct operative engagement between the blade and the actuating member being effected by means of a track or guide-way on one of said parts oblique to both directions of reciprocation and a follower on the other part operating in said guide-way.
3. In the combination defined in claim 1, the direct operative engagement between the blade and the actuating member being effected by means of a slot in the blade oblique to both directions of reciprocation and a part projecting from the actuating member into the slot.
4. In a safety razor, a reciprocating cutting blade, guides for said blade, said blade having a centrally disposed, oblique slot adapted to receive a driving pin; a frame; traction rollers journaled in the frame, a crankshaft rotatable by said rollers, a pitman driven from the crankshaft and provided with a driving pin for the blade, and means to guide the pin.
5. In a safety razor, a frame comprising a sheet metal yoke provided with seats for top and bottom frame-plates and having a pair of opposite lateral portions bent at obtuse angles from the middle portion, the end of each lateral portion being bent hookwise to form channels for frame-rivets.
6. In the combination defined in claim 5, the middle portion of said yoke having a handle-attachment lug thereon, bent at substantially a right angle to the adjacent portion of the yoke.
7. In a safety razor, a frame comprising a sheet metal bottom-plate, a sheet metal blade-supporting plate spaced therefrom, a

sheet metal yoke holding said parts in spaced relation, and rivets fastening said three parts together.

8. In a safety razor, a frame comprising a blade-supporting plate and a guard member hingedly connected to one edge of said supporting plate to overlie the blade; means integral with said guard and co-acting means integral with the supporting plate for holding the guard closed over the blade.

9. In the combination defined in claim 8, said holding means being frictionally engageable for retaining the blade.

10. In the combination defined in claim 8, said hinged guard member being movable axially of its hinge for engaging or disengaging the said integral holding means by moving one of them into or out of registration with the other.

11. In a safety razor, a frame-plate having in one longitudinal edge a pair of longitudinal slots, the metal between said slots and the edge of the plate being non-circular in section, a lug projected from said plate between said slots, a guard-plate having on its rear edge integral hinge elements engaging the metal portions above specified, and a lug projected from the hinged edge of the guard for engagement with the first-named lug for the purpose described.

12. In a safety razor, a frame comprising a blade-supporting plate and a movable guard hinged to said plate to overlie the blade for retaining it, the hinge pivot being non-circular and the co-acting part of the hinge embracing it yieldingly for yieldingly holding the guard in open position.

13. As an improved article of manufacture, a razor blade of the wafer type, provided with a centrally positioned slot, said slot being elongated and extending obliquely to the cutting edge of the blade.

14. As an improved article of manufacture, a razor blade of the wafer type, provided with a centrally positioned slot, said slot being V-shaped in outline, of uniform breadth from end to end thereof, and being symmetrical to a line bisecting the blade longitudinally.

In testimony whereof, I have hereunto set my hand at Chicago, Illinois, this 19th day of May, 1922.

GEORGE BROWNING.
